US00D819802S

(12) **United States Design Patent** (10) **Patent No.:** **US D819,802 S**
(45) **Date of Patent:** **** Jun. 5, 2018**

(54) **CATHETER ADAPTER**

- (71) Applicant: **Becton, Dickinson and Company**, Franklin Lakes, NJ (US)
- (72) Inventors: **Jonathan Karl Burkholz**, Salt Lake City, UT (US); **Ralph L. Sonderegger**, Farmington, UT (US); **Bart D. Peterson**, Farmington, UT (US); **Bin Wang**, Sandy, UT (US); **Nathan Mitchell**, Murray, UT (US)
- (73) Assignee: **Becton, Dickinson and Company**, Franklin Lakes, NJ (US)
- (**) Term: **15 Years**
- (21) Appl. No.: **29/580,130**
- (22) Filed: **Oct. 5, 2016**
- (51) LOC (11) Cl. **24-02**
- (52) U.S. Cl. **D24/112; D24/129**
- (58) **Field of Classification Search**
USPC D24/112, 114, 127, 128, 129, 130, 133, D24/141, 146, 147; D8/93, 97, 300, 310, D8/311
CPC .. A61M 5/158; A61M 5/1582; A61M 5/3243; A61M 2005/1583; A61M 2005/1586; A61M 2005/3227; A61M 25/0606; A61M 25/0612; A61M 25/0631; A61M 25/0637

(57) **CLAIM**

The ornamental design for a catheter adapter, as shown and described.

DESCRIPTION

FIG. 1 is a perspective front, top and side view of a catheter adapter.

FIG. 2 is a perspective front, top and side view thereof.

FIG. 3 is a front view thereof.

FIG. 4 is a rear view thereof.

FIG. 5 is a right side view thereof.

FIG. 6 is a left side view thereof.

FIG. 7 is a top view thereof.

FIG. 8 is a bottom view thereof.

FIG. 9 is a perspective front, top and side view of a catheter adapter showing a second embodiment.

FIG. 10 is a perspective front, top and side view thereof.

FIG. 11 is a front view thereof.

FIG. 12 is a rear view thereof.

FIG. 13 is a right side view thereof.

FIG. 14 is a left side view thereof.

FIG. 15 is a top view thereof; and,

FIG. 16 is a bottom view thereof.

The broken lines depict portions of the catheter adapter that form no part of the claimed design.

1 Claim, 12 Drawing Sheets
